IRONING MACHINE CABINET

David A. Lundy, Riverside, Ill.

Application November 25, 1938, Serial No. 242,242

34 Claims. (Cl. 312—29)

This invention relates to ironing machines, and has to do with ironing machines of the table top type, in which the ironing members and associated parts are disposed within an enclosing structure, when not in use, which structure then provides a top available for use as a table or for analogous purposes.

My invention is directed to—an ironing machine of the character stated in which closure members of the enclosing structure also function to support the ironing instrumentalities and certain of such members are disposed in cooperating relation to the ironing members for supporting articles being ironed and articles which have been or are to be ironed, during the ironing operation; providing means whereby the closure members may be moved to full open operative positions, for cooperation with the ironing members, with expedition and facility, and are adequately supported in such positions; so relating the closure members that certain thereof may be moved into open positions independently of the other closure members, where desired, leaving the front of the enclosing structure unobstructed and rendering the structure available for use as a writing desk or table; the provision of means yieldingly urging the ironing members into exposed position for use and controlling movement thereof into the enclosing structure, in conjunction with means for locking the ironing members in position within the enclosing structure and means actuated by opening of one of the closure members for releasing the ironing members, the latter means preferably also limiting opening movement of the associated closure member; and the provision of means for raising the ironing members into position exposed for use and for cushioning lowering thereof into the enclosing structure, such means exerting a substantially constant force throughout movement of the ironing members in either direction.

More specifically, the enclosing structure comprises end members, a top cover, and doors for closing the front of the structure. The doors, when closed, fit into appropriate recesses formed in the end members, covering the upper portions thereof and being flush with the lower portions and the outer faces of the end members and disposed beneath the forward portion of the cover. The structure as a whole then presents a neat and attractive appearance and presents a minimum number of cracks when viewed from in front. The bed plate, which carries the ironing means, is pivoted to the end members and serves also as bracing means therefor, in the nature of a connecting rod, effective for maintaining the rearward portions of the end members in proper spaced relation to one another. If desired, the upper rearward portions of the end members may be connected together by a

spacing rod, providing a rigid brace, upon which the bed plate may be pivoted. The position of the pivotal axis of the bed plate may, of course, be varied to accommodate the particular ironing means. The bed plate, or the spacing rod, connecting the rearward upper portion of the end members, cooperates with a brace connecting the forward upper portions of the end members, for securing the latter in spaced, parallel relation. Further objects and advantages of my invention will appear from the detailed description.

In the drawings:

Figure 1 is a front view of an ironing machine embodying my invention, with the ironing members disposed within the enclosing structure and the closure members of the latter in closed positions;

Figure 2 is a plan view of the machine of Figure 1, on a reduced scale, with the ironing members raised into position available for use and the closure members of the enclosing structure in open positions disposed for cooperation with the ironing members;

Figure 3 is a front view of the machine conditioned for use in ironing, as in Figure 2;

Figure 4 is a sectional view taken substantially on line 4—4 of Figure 1, certain parts being shown in elevation and the channel member at the upper front portion of the enclosing structure being sectioned in a plane adjacent the left-hand end of the machine, the head of the machine, including the ironing members and associated parts, being in lowered position;

Figure 5 is a view similar to Figure 4 but with the head of the machine in raised position with the ironing members exposed available for use;

Figure 6 is a fragmentary sectional view, on an enlarged scale, taken substantially on line 6—6 of Figure 2, with the cover in full open position;

Figure 7 is a view similar to Figure 6, with the cover moving in opening direction and approaching its full open position;

Figure 8 is a view similar to Figure 7 but with the cover moving in closing direction and in a position a short distance from its full open position;

Figure 9 is a fragmentary sectional view taken substantially on line 9—9 of Figure 8;

Figure 10 is a sectional view taken substantially on line 10—10 of Figure 8;

Figure 11 is a sectional view taken substantially on line 11—11 of Figure 2, on an enlarged scale;

Figure 12 is a sectional view taken substantially on line 12—12 of Figure 11, certain parts being shown in elevation;

Figure 13 is a sectional view, on an enlarged scale, through the righthand end member of the enclosing structure, taken substantially on line

13—13 of Figure 5, certain parts being shown as partly broken away and in elevation;

Figure 14 is a fragmentary sectional view, on an enlarged scale, through the lefthand corner portion of the cover and the adjacent portion of the lefthand end member of the enclosing structure, taken substantially in the plane of line 14—14 of Figure 1, certain parts being shown in elevation;

Figure 15 is a view similar to Figure 14 but showing the manner in which the cover is released for opening;

Figure 16 is a view on the order of Figure 14 but with the cover moving in closing direction and approaching its full closed position;

Figure 17 is a view taken substantially on line 17—17 of Figure 14, with the cover and the associated end member of the enclosing structure broken away;

Figure 18 is a fragmentary vertical sectional view, on an enlarged scale, through the upper inner corner portion of the righthand door of the enclosing structure and the adjacent portion of the cover, the latter and the door being in full closed position, the lefthand door being shown fragmentarily and in elevation, certain parts being shown in elevation, this view being taken substantially on line 18—18 of Figure 19;

Figure 19 is a sectional view taken substantially on line 19—19 of Figure 18, the righthand door being shown partly broken away and in section;

Figure 20 is a sectional view, on an enlarged scale, taken substantially on line 20—20 of Figure 1, certain parts being shown in elevation and certain other parts being omitted for clearness of illustration;

Figure 21 is a fragmentary lengthwise vertical sectional view taken through the front top channel member of the enclosing structure, adjacent the lefthand end member of such structure, illustrating the cam and associated parts for releasing the lefthand door upon movement of the ironing means into exposed position available for use;

Figure 22 is a fragmentary front view of the left end portion of the enclosing structure, with the left door in open position at right angles to the adjacent end member;

Figure 23 is a view similar to Figure 22, but with the left door in position providing a support for articles being ironed;

Figure 24 is a sectional view taken substantially on line 24—24 of Figure 1, on an enlarged scale, with certain parts shown in plan;

Figure 25 is a fragmentary plan view of the left portion of the machine with the left door in the position of Figure 23 and the ironing members in raised position and exposed available for ironing, showing the relation between the ironing members and the left door;

Figure 26 is a left hand view of the ironing machine with the left door in position to provide a support for articles being ironed but at right angles to its position shown in Figure 25;

Figure 27 is a sectional view taken substantially on line 27—27 of Figure 26, partly broken away and showing the brace for the left door in elevation;

Figure 28 is a sectional view taken substantially on line 28—28 of Figure 27, the left end member of the enclosed structure being shown partly in section and partly in plan;

Figure 29 is a sectional view taken substan-

tially on line 29—29 of Figure 5, on an enlarged scale;

Figure 30 is a plan view of a modified form of ironing machine embodying my invention;

5 Figure 31 is a sectional view taken substantially on line 31—31 of Figure 30, on an enlarged scale;

Figure 32 is a sectional view taken substantially on line 32—32 of Figure 30, on an enlarged scale, certain parts being shown in elevation;

10 Figure 33 is a fragmentary vertical sectional view, on an enlarged scale, through the cover and the upper inner portion of the righthand door of the machine of Figure 30, with this door and the cover in closed position, showing the sliding pivot connection between the cover and the door, parts being shown in elevation;

15 Figure 34 is a sectional view, on an enlarged scale and partly broken away, taken substantially on line 34—34 of Figure 30;

20 Figure 35 is a view similar to Figure 5 but showing a modification of the means for raising the bed plate and the parts carried thereby and for controlling lowering of the bed plate;

25 Figure 36 is a sectional view, on an enlarged scale, taken substantially on line 36—36 of Figure 35, certain parts being shown partly broken away and in section and certain other parts being shown in plan; and

30 Figure 37 is a fragmentary sectional view through the lefthand end member of the enclosing structure and the adjacent portion of the bed plate, taken substantially on line 37—37 of Figure 35.

35 The enclosing structure, within which the ironing machine is housed, when not in use, comprises lefthand and righthand end members 40 and 41, respectively, conveniently formed of sheet metal, each being cubiform and comparatively

40 thin relatively to its height and width, each end member comprising inner and outer walls as well as front, back, top, and, if desired, bottom walls. Each of the end members 40 and 41 is provided, at its lower end, with a depending apron 42, conveniently formed of sheet metal, and these aprons are connected, at the midpoints thereof, by a sheet metal brace 43 of channel cross section, as will be clear from Figure 4. Aprons 42 house casters *f* of known type, upon which the machine

50 is mounted, and are provided with corner bumpers *g* of rubber or other suitable material. The parts of the structure so far referred to, as well as other parts to be hereinafter named, may be secured together in any suitable manner, conveniently by welding. Each of the end members

55 is of stepped construction to provide, at the front thereof, a projecting shoulder 44 for a purpose to be described presently, and the upper forward corners of the end members are connected by a

60 brace 45 of channel cross section, as will be clear from Figures 2, 3, and 4. A bed plate 46 extends between the end members 40 and 41, this plate being pivoted at its rearward corner to the upper rearward corners of the end members. Referring to Figures 4, 5, and 29, a bearing bracket 47 is suitably secured to each rear corner of said plate 46, conveniently by bolting, this bracket receiving a headed pivot pin 48 which passes through a bearing collar 49 welded to the inner

70 wall of the end member, pin 48 projecting outward a short distance between this inner wall and receiving a stop member, such as a cotter pin 50, there being a washer 51 disposed between pin 50 and the adjacent wall of the end member. It will be seen that bed plate 46 is thus piv-

oted between the end members for swinging movement about an axis extending lengthwise of the enclosing structure adjacent the rearward edge of the bed plate. The latter may be swung downward into the position shown in Figure 4, in which position it provides a closure for the back of the enclosing structure, or it may be swung upward into the position shown in Figure 5, being of such width as to extend into proximity to the channel member 45 and to provide a closure for the top of the enclosing structure. The bed plate 46 may be formed of any suitable material and in any suitable manner. Conveniently it is formed of sheet metal and preferably is provided with a bottom wall 52 presenting a substantially continuous and smooth surface to the exterior of the enclosing structure, when the bed plate is in its lowered position shown in Figure 4.

Bed plate 46 provides mounting means suitable for reception of ironing means of suitable type. The ironing means illustrated by way of example comprises a gear housing *h* disposed adjacent one end of bed plate 46, a padded iron roll *r* extending from the gear housing above the bed plate toward the other end thereof and terminating adjacent said other end, a shoe *s* cooperating with the roll *r*, the roll and the shoe constituting the ironing members of the ironing means, and an electric motor and associated means for rotating the roll and imparting relative movement to the roll and the shoe for moving them into and out of cooperating relation. The electric motor may be disposed within the gear housing *h* or it may be disposed within the roll *r*, as is well known in the art, and need not be shown. It will be understood, of course, that suitable means may be provided for controlling operation of the ironing means and, if desired, the ironing means may embody an electric motor disposed exterior of both the roll and the gear housing, such motor conveniently being arranged beneath the bed plate 46. Ironing means of that character are well known in the art and need not be illustrated nor described in greater detail. Briefly, the bed plate 46 provides convenient means for mounting ironing means of any suitable known type for cooperation with the enclosing structure, it being understood that a suitable electric cord or cable (not shown) is provided for connecting the electric motor to a suitable source of supply of electrical energy.

A bracket 55, of approximately Z shape, is suitably secured to each forward corner of bed plate 46 and projects downwardly therefrom, this bracket being provided with a lower forwardly projecting arm 56 which, in the raised position of bed plate 46, extends beneath channel member 45 and cooperates therewith for preventing upward movement of bed plate 46 beyond its position shown in Figure 5. Each bracket 55 is provided with a pin 57, projecting outward therefrom through an arcuate slot 58 in the inner wall of the adjacent end member, this slot being concentric with the pivot about which the bed plate 46 swings. In the lowered position of the bed plate, shown in Figure 4, the pins 57 are disposed in rear of and in contact with the rearward ends of locking bars 59 pivoted at 60 in the end members. In Figures 4 and 5 the locking bar 59 mounted in end member 40 is shown, and it will be understood that a similar locking bar is mounted in end member 41. Each locking bar 59 has its forward end urged downward by a coil tension spring 61 anchored at its upper end to bar 59, forward of pivot 60, the lower end of said

spring being suitably anchored to end member 40, between the walls thereof. Upward movement of the rearward portion of bar 59 is limited by a stop pin 62 secured to the inner wall of the corresponding end member. It will be clear from Figures 4 and 5 that when the bed plate 46 is swung downward, from the position shown in Figure 5 into the position shown in Figure 4, the rearward ends of the locking bars 59 are depressed by the pins 57 which then pass into the rear lower ends of the slots 58, beyond the rearward ends of bars 59, these bars being then returned to locking position by the tension springs 61, in which position the rearward ends of the locking bars are disposed in front of pins 57, in position effective for holding the bed plate 46 in its normal lowered position, shown in Figure 4. In that position of the bed plate the ironing means, including the ironing members *r* and *s* and associated parts, are disposed between the end members below the top thereof and between the front and the back of the end members.

Means is provided for raising the bed plate 46 from its position shown in Figure 4 into its upper position shown in Figure 5. Referring particularly to Figures 4, 5, and 13, a coil tension spring 65 is disposed within each of the end members and has its lower end suitably anchored to a bracket 66 appropriately secured in the end member at the lower rearward corner thereof. The upper end of spring 65 is suitably anchored to a pulley block 66 carrying a grooved sheave or pulley 67. A cable 68 is passed beneath pulley 67 and has one end anchored to a pin 69 secured in and projecting inward from a collar 70 secured to the outer and top walls of the end member. The portion of the cable between pin 69 and pulley 67 constitutes one run thereof, and the other run of this cable is led over a grooved pulley 71 rotatably mounted in a bracket 72 secured to and depending from the top wall of the end member, the other end of this cable being anchored to pin 57. It will be seen that the springs 65 are under maximum tension, when bed plate 46 is in its lowered position shown in Figure 4, and serves to swing the bed plate upward and forward into its full raised position shown in Figure 5, when the locking bars 59 are moved into releasing position. Springs 65 may be of such strength as to swing the bed plate 46 into its completely raised position, or they may be of sufficient strength to raise the bed plate into a position somewhat lower than its completely raised position, the bed plate being moved into the latter position by hand. In this connection, it will be noted that the arms 56 of the brackets 55 are of appreciable extent lengthwise of the bed plate and may be readily grasped for raising it. When bed plate 46 is in its full raised position shown in Figure 5, the springs 65 are under reduced tension, and upon downward movement of the bed plate into the enclosing structure the tension of the springs increases, the latter then being effective for controlling and cushioning movement of the bed plate and the parts carried thereby into the enclosing structure.

Suitable means is provided for releasably securing the bed plate in its raised position. Referring to Figures 6 to 10, inclusive, latch members 75 and 75a are pivotally mounted in channel member 45, adjacent the ends thereof, each upon a shouldered screw-pin 76 passing through a hub 77 integral with the latch member. Each 75 of the latch members 75 and 75a projects through

a slot 78 in the inner wall of the adjacent end member and is provided with a hook bill 79, disposed to engage beneath the end portion of arm 56 of the adjacent bracket 55, when bed plate 46 is in its full raised position. Each latch member is provided with an arcuate slot 80 concentric with pivot pin 76, which slot receives a finger 81 at the upper end of and perpendicular to a link 82 in the form of a rod. This link is provided, at its lower end, with a finger 83 perpendicular to the link and passing through the forward end of the adjacent locking bar 59. When the latch members 75 and 75a are in their normal position, shown in Figures 6 and 7, the fingers 81 are in contact with the respective latch members at the lower end of the slot 80. It will be apparent that the tension springs 65 are effective, through the locking bars 59 and links 82, for yieldingly resisting outward movement of the latch members 75 and 75a and urging the latter into normal latching position. In that position of the latch members, when the bed plate 46 is swung into its uppermost position, latch members 75 and 75a will be moved outward by contact of arms 56 of the brackets 55 with the hook bills 79 and, when arms 56 contact the channel member 45, the latch members 75 and 75a will be returned to normal position, with the hook bills 79 engaging beneath arms 56 and effective for holding the bed plate 46 raised, the latch members and channel member 45 then cooperating with arms 56 to lock the bed plate against movement in either direction about its pivotal axis.

An angle release lever 85 is pivotally mounted in channel member 45 at the mid-length thereof, by means of a shouldered pivot screw 86 passing through a hub 87 integral with lever 85. One arm of lever 85 is connected, above and below pin 86, to the latch members 75 and 75a, by means of links 88, the latter being connected to the latch members 75 and 75a below the pivot pin 76 thereof, and the connections between links 88 and the arm of lever 85 being such that latch members 75 and 75a are moved outward, when lever 85 is turned clockwise as viewed in Figure 11. The other arm 89 of lever 85 extends toward the lefthand end of the enclosing structure, between the depending flanges of channel member 45, and is provided, at its underface, with a depending pad 90 of rubber or other suitable material. A coil tension spring 91 is anchored at one end to lever 85 at a point above pin 86, the other end of said pin being suitably anchored to channel member 45, the tension of spring 91 being effective for urging the lever 85 in clockwise or releasing direction. Tension spring 91 is not of sufficient strength to overcome the tension of springs 65, and serves merely to hold the latch members 75 and 75a in such position that the fingers 81 contact the walls at the lower ends of the slot 80. By moving arm 89 of lever 85 upward, the latch members 75 and 75a may be swung outward into inoperative position, in opposition to the tension of springs 65, thus releasing the bed plate 46 for downward movement. This outward movement of the latch members 75 and 75a results in raising the forward ends of locking bars 59 and depressing the rearward ends thereof, but that is not objectionable, since the lever 85 is operated but momentarily and then released, the locking bars 59 being returned to operative or locking position before the bed plate 46 reaches its full lowered position, in which it is held by the locking bars in the manner previously described.

When the ironing means is disposed within the enclosing structure, as in Figure 4, the top of this structure is closed by a cover 92. This cover may be of any suitable construction but conveniently is formed of sheet metal and is provided, at its underface, with an inwardly projecting peripheral flange 93 of appreciable width. Cover 92 is pivotally connected, at its right rear corner, to the upper rear corner of the righthand end member 41. Referring to Figure 6, a headed pivot pin 94 passes through a bracket 95 secured in end member 41 and thence upward through the top wall of this end member and through flange 93 of cover 92 at the rear righthand corner thereof. Pin 94 is reduced in diameter at its upper portion and threaded to provide a screw stud 96 receiving a nut 97, there being a washer 98 disposed between this nut and the upper face of flange 93. That provides convenient means for pivoting the cover 92 to the enclosing structure, in the manner stated, though the cover may be mounted in any other suitable or appropriate manner. The front and back ends of the cover 92 are rounded and, when in full closed position, the cover seats upon the top of end members 40 and 41 with its ends flush with the outer faces of the latter members, its rearward edge flush with the rearward edges of the end members 40 and 41 and its forward portion seating upon and projecting a short distance forwardly of the channel member 45, as will be clear from Figures 1 and 4.

Referring further to Figures 6 to 10, inclusive, the portion of flange 93 at the rear of cover 92 is provided with an inwardly extending projection 100 carrying, at its inner portion, an upwardly and outwardly inclined cam element 101 which overlies a rectangular opening 102 through projection 100. The latter is further provided with a relatively narrow slot 103 extending outward from the rearward portion of opening 102. Latch member 75a is provided with an upwardly projecting arcuate finger 104 concentric with pivot pin 76, at the upper end of which finger there is mounted a roller 105 projecting from the finger rearwardly of end member 41. Finger 104 projects through a slot 106 in the top wall of end member 41, when latch member 75a is in its operative position shown in Figure 6. When cover 92 is in its closed position shown in Figures 1 and 4, at which time the bed plate 46 is in its lowered position, the flange 93 at the righthand end of cover 92 seats upon the top wall of end member 41 and may contact with roller 105, holding the latch member 75a depressed in the position shown in Figure 8. It will be understood that, if desired, flange 93 may be provided, at the righthand end of cover 92, with a suitably disposed notch or opening which accommodates the finger 104, in which case the latch member 75a may remain in the position shown in Figure 6 when the cover 92 is in closed position. The provision of such a notch or opening in flange 93, for the purpose stated, is an obvious expedient which need not be illustrated nor described in greater detail. During movement of the cover 92 from closed position to its open position, latch member 75a remains in the position shown in Figure 6 until cover 92 approaches full open position, at which time the inner portion of projection 100 passes beneath roller 105. In the continued opening movement of the cover 92, cam element 101 passes beneath roller 105 and forces latch member 75a upward in counterclockwise direction about pivot pin 76, as in Figure 7. This up-

ward movement of the latch member 75a imparts similar movement to latch member 75, due to the interconnection between these latch members previously described, thus moving the locking bars 59 into releasing position and releasing the bed plate 46 for upward movement. As movement of cover 92 continues in opening direction, cam element 102 passes from beneath roller 105, latch member 75a is returned to its position shown in Figure 6, and finger 104 enters slot 103, in contact with the projection at the outer end of said slot and with roller 105 overlying projection 100, as shown in Figure 6. That limits opening movement of cover 92 and prevents its being turned into position beyond that shown in Figure 2, in which the rear edge of the cover, when in closed position, is flush with the inner face of righthand end member 41, the cover seating upon this end member for a suitable portion of its length and projecting therefrom forwardly of the enclosing structure. It will be seen that the means for limiting opening movement of the cover also serves to release the means for holding the bed plate 46 in lowered position, opening of the cover thus serving to cause movement of the bed plate and the parts carried thereby into operative position, with the ironing members above the enclosing structure exposed available for use, and the cover disposed with its length at right angles to the width of the enclosing structure, adjacent the righthand end of the ironing members, available as a support for articles to be ironed and which have been ironed.

When it is desired to lower the ironing means into the enclosing structure, latch members 75 and 75a are moved into inoperative positions by means of the release lever 85, in the manner previously described, bed plate 46 and the parts carried thereby then swinging downward into the enclosing structure under control of the tension springs 65, in the manner previously described, the locking bars 59 functioning to lock the bed plate in its lowered position. The cover 92 may now be swung into closed position for closing the top of the enclosing structure and rendering it available for use as a table or for analogous purposes. During closing movement of the cover, cam element 101 contacts roller 105 swinging the latch member 75a clockwise about pivot pin 76 downward into the position shown in Figure 8. Corresponding movement is imparted to the latch member 75 by the interconnection between these latch members. This movement of the latch members does not affect the locking bars 59, due to the lost motion permitted by the slots 80, so that the bed plate 46 remains locked in its lowered position. In the continued closing of cover 92, projection 100 passes out of contact with roller 105 and latch member 75a is returned to its position shown in Figure 6, in which position it remains throughout the rest of the closing movement of cover 92, assuming the flange 93 at the righthand end of cover 92 to be provided with a notch or opening which accommodates finger 104. In the event no such opening is provided, latch member 75a will be again depressed, by flange 93, as the cover is moved into full closed position, but that would not be objectionable since it would not affect the locking bars 59, for the reasons previously stated. The movements of latch member 75a cause similar movements of latch member 75, due to the connection between the latch members through the angle release lever 85 and the link 88.

Appropriate means is provided for securing

the cover 92 in closed position. Referring to Figures 14 to 17, inclusive, cover 92 is provided, at the back and adjacent the lefthand end thereof, with an inwardly projecting thimble 110 formed integrally with the back wall of the cover. A rod 111 is slidably mounted through thimble 110 and through the lower end of an angle bracket 112 secured to and depending from the top wall of cover 92. Rod 111 is urged outward by a coil compression spring 113 mounted about the rod and confined between bracket 112 and a lock collar 114 secured upon rod 111 and contacting the inner end of thimble 110, for limiting outward movement of the rod. Inner end portion 113a of rod 111 is flat and has pin and slot connections 115 to arm 116 of an angle lever 117, pivoted at 118 on a bracket 119 secured to and projecting upward from flange 93 of cover 92. The other arm 120 of lever 117 is provided, at its inner end, with a downwardly projecting element 121 adapted for operation in a corresponding slot 122 through flange 93, it being noted that the height of element 121 does not exceed the thickness of flange 93.

When cover 92 is in its full closed position, slot 122 is aligned with a slot 123 through the top wall of end member 40. These aligned slots receive an element 124 of inverted V-shape, projecting from the upper edge of a latch member 125 pivoted at its forward end, at 126, within end member 40 of the enclosing structure. Latch member 125 is yieldingly held in its raised position, shown in Figure 14, in contact with the underside of the top wall of end member 40, by a leaf spring 127 secured to a bracket 128 of substantially Z-shape in cross section (Figure 27), suitably secured within end member 40. Latch member 125 is provided, at its rearward end, with an upwardly projecting bill or locking element 130 which, in the closed position of cover 92, extends through registering openings or slots 131 and 132 in flange 93 and the top wall of end member 40, respectively, thus positively locking the cover closed. In order to release cover 92, rod 111 is forced inwardly or forwardly, as indicated by the arrow in Figure 15, thus swinging arm 120 of lever 117 downward into contact with element 124, moving the latch member 125 into its inoperative position shown in Figure 15, thus releasing the cover and permitting movement thereof in opening direction, indicated by the arrow in Figure 15. When the cover has been moved a short distance in such direction, element 121 passes out of contact with element 124 but, at that time, slot 131 is out of register with slot 132 and, thereafter, member 125 is ineffective for locking cover 92 against movement in opening direction. When cover 92 is moved in closing direction, as indicated by the arrow in Figure 16, flange 93 at the rear of the cover contacts element 124 and, by camming action therewith, moves latch member 125 into its inoperative position, holding it in that position until the cover is fully closed, at which time slots 122 and 123 are aligned and slot 131 is in register with slot 132, member 125 being then returned to its position shown in Figure 14, by leaf spring 127, and locking the cover closed in the manner above described.

Suitable closure means is provided for the front of the enclosing structure. This means comprises a lefthand door 134 and a righthand door 135. These doors, when in closed position, extend from the shoulders 44 of the end members 40 and 41, and underlie the portion of cover

92 which projects forwardly beyond channel member 45, in the closed position of cover 92, as will be clear from Figure 4. The righthand door 135 is suitably secured, at its outer end, upon a rod 136 (Figure 1 and Figure 3) mounted for turning movement in a bracket 137 suitably secured within the righthand end member 41, below shoulder 44 thereof, this rod extending upward through door 135 and being mounted, at its upper end, in an extension 138 of the top wall of member 41, the top wall of door 135 having an appropriate depression which accommodates the extension or element 138. A torsional coil spring 139 is mounted about rod 136, below bracket 137, one end of this spring being anchored to the bracket and the other end of this spring being anchored to the rod, in an appropriate manner. Spring 139 urges the door 135 in opening direction. Door 135 conveniently is of sheet metal construction, is cubiform and is comparatively thin relative to its height and width. This door is provided, in its top wall, with a lengthwise slot 140 (Figure 18) which receives a reduced element 141 of a pin 142 provided, at its upper end, with a reduced screw stud 143 extending through flange 93 at the front of cover 92. A nut 144, threaded upon screw stud 143 and bearing against the upper face of flange 93, cooperates with element 141 for securing pin 142 to flange 93, there being a jam nut 145 screwed upon stud 143 in contact with nut 144. Pin 142 may be secured to flange 93 in any other suitable manner. Preferably, pin 142 is provided with an outwardly projecting flange 146, at the lower end of element 141, the height of the latter being approximately equal to the thickness of the top wall of door 135, and the diameter of element 141 being equal to the width of slot 140, so that flange 146 holds the cover 92 against upward movement relative to door 135. When cover 92 is swung into open position, door 135 is also swung into open position, due to the sliding pivot connection provided by the pin 142 and slot 140, door 135 extending from end member 41 beneath cover 92 transversely thereof, in the full open position of the cover, thus providing supporting means for the latter supplemental to the end member 42. This assures that the cover, in its full open position, is effectively supported and braced. When cover 92 is returned to closed position, door 135 is also returned to closed position, in which position it is held by the cover, the latter being locked in full closed position in the manner previously described.

Under certain conditions, to be hereinafter described, it is desirable that the door 135 be capable of being opened independently of cover 92. For that purpose, I provide means whereby the pin 142 may be released from door 135 when desired. Referring to Figures 18 and 19, the top wall of door 135 is provided with a slot 148, extending rearward from the inner end of slot 140 and opening through the inner or back wall of door 135. Slot 148 opens into the upper end of a slot 149 through the inner or back wall of door 135, such latter slot being of proper size and shape to accommodate the pin 142. Normally, slot 149 is covered by a plate 150 projecting upward from a downwardly tapering cam member 151 disposed within door 135, at the inner face of the back wall thereof, this cam member being mounted upon a squared shaft 152 provided, at its rearward end, with a reduced cylindrical element 153 mounted for rotation in the back wall of door

135. Shaft 152 is further provided, at its outer or forward end portion, with a reduced cylindrical element 154 mounted for rotation in an annulus 155 secured within a depression 156 in the outer or front wall of door 135. A knob 157 is suitably secured to the forward end of shaft 152 for turning the latter. An appropriately formed leaf spring 158 is secured to a bracket 159, secured upon the inner face of the back wall of door 135, and is in contact with the lower portion of cam member 151. Normally, spring 158 engages about the lower tapered portion or nose of cam member 151, holding the latter in the position shown in Figure 18, with plate 150 extending across the slot or opening 149, preventing passage of pin 142 therethrough. Accordingly, at such time, door 135 will be moved within the cover 92 in the opening and the closing movement thereof. When it is desired to open door 135 independently of cover 92, cam 151 is turned into the dotted line position shown in Figure 18, at which time the plate 150 is disposed from in front of slot 149, leaving the latter unobstructed for passage of the pin 142. The door 135 may then be opened independently of the cover 92, as will be obvious. It will be noted that in the dotted line position of cam member 151, the inner end of spring 158 bears upon this cam member so as to urge the latter in a clockwise direction, edge 151a of cam member 151 then contacting the inner face of the inner end wall of door 135 and limiting turning movement of the cam member. In the full line position of cam member 151, a projection or shoulder 151b thereof contacts the inner face of the inner end wall of door 135 limiting turning movement of the cam member in counterclockwise direction, in which direction the cam member is urged by the spring 158, when in its normal position. That assures that plate 150 will be properly positioned correspondingly to the cam member, in each position thereof, while preventing turning of the cam member to an improper extent in either direction. Door 135, when released from cover 92, may be held in open position by any suitable known means, which need not be illustrated nor described in detail.

Door 134 is constructed similarly to door 135 except that it has no back or inner wall. When in closed position, door 134 extends from shoulder 44 of the lefthand end member 40 to the under face of cover 92, the forward portion of which it underlies. Referring to Figures 22 to 26, inclusive, a hinge plate 161 is secured to the inner face of the outer wall of the lefthand end member 40, within the latter, and is provided at its upper and lower forward corners with a suitably bored boss 162. These bosses receive a pintle rod 163, suitably secured therein, the end portions of which pass through the inner ends of hinge links 164, disposed above the upper boss 162 and below the lower boss 162. End member 40 is provided, at its forward outer corner, with slots 165 through which the links 164 project. One arm 166 of a U-shaped bale 167 is mounted for turning movement through the outer ends of links 164, and is confined against relative upward movement therethrough by a stop collar 168 secured upon arm 166, at the lower face of the lower link 164. A bracket 169 is pivoted upon the other arm 170 of bale 167, the upper end of this latter arm being connected to the upper end of arm 166 by a brace 171, one end of which is secured upon the arm 166 at the upper face of the upper link 164, effective for confining arm 166

against downward movement relative to the hinge links. The other end of brace 171 is secured upon the upper end of arm 170, at the upper face of a sleeve 172 of bracket 169, through which sleeve arm 170 passes, effective for confining bracket 169 against upward movement relative to arm 170. Downward movement of bracket 169 on arm 170 is prevented by a stop collar 173, secured upon arm 170 in contact with the lower end of a sleeve 174 carried by bracket 169, the latter sleeve being aligned with sleeve 172 and receiving arm 170. Bracket 169 is provided, at its upper end with two pairs of sleeves 175 and 176, which receives between them sleeves 177 depending from the inner or rearward edge of the top wall of door 134 and conveniently formed integrally therewith. A pintle rod 178 passes through the aligned sleeves 175, 176, and 177, the ends of this rod being suitably secured in the sleeves 175. In this manner the door 134 is connected to end member 40 for universal movement, being capable of being swung into position extending either forwardly from end member 40 or outwardly from the outer face thereof, while in parallel relation to the bracket 169, and also capable of movement about pintle rod 178 into position parallel with bracket 169 or into position perpendicular to the bracket, in which latter position door 134 is disposed horizontally above the upper end of the bracket.

Referring to Figure 20, door 134 is held closed by a latch member 180 pivoted on a pin 181 secured to the inner end wall of door 130. This latch member is urged upward by a leaf spring 182 secured to the front wall of door 134, at the inner face thereof, and is provided at its inner end with a bill 183 having an upwardly and outwardly inclined surface, and a flattened or horizontal area at its upper end. Latch member 180 is further provided, at the outer face of bill 183, with an upwardly projecting lug 184 disposed for engagement in a corresponding slot 185 extending from the lower edge of the forward flange of channel member 45. It will be noted that, in the closed position of door 134, bill 183 extends upward at the rearward or inner face of the outer flange of channel member 45, confining door 134 against forward opening movement, and lug 184 engaging in slot 185 confines this door against outward lengthwise movement, thus providing means effective for holding the door in closed position. In order that door 134 may be released manually for opening, a cam member 187 is secured upon the inner end of a stud 188 rotatably mounted through the front wall of the door, a knob 189 being suitably secured upon the outer end of this stud. Cam member 187 is so disposed that by turning the knob 189 in clockwise direction, as viewed in Figure 18, the latch member 180 may be moved down into releasing position, thus permitting of door 134 being moved into open position, extending forward from the end member 40. With the doors 134 and 135 open, the front of the enclosing structure is unobstructed and it is then available for use as a writing desk, or for analogous purposes, the cover 92 providing a flat surface serving as a table or desk top. Referring to Figure 4, it will be noted that when bed plate 46 is in its lowermost position, the forward edge thereof is spaced a considerable distance from the front of the enclosing structure, providing ample unobstructed space to permit of a person being seated with comfort at the front of the structure while using it as a writing table or desk.

The door 134, when in closed position, is yieldingly urged outward by appropriate means. A plunger 191 (Figure 20) is slidably mounted through a bracket 192 secured to and depending from the top wall of door 134. This plunger is provided, at its inner end, with a bumper 193, formed of rubber or other suitable material, between which bumper end bracket 192 is confined a coil compression spring 194, disposed about plunger 191, this spring being placed under compression by contact of bumper 193 with the forward face of channel member 45, when door 134 is in closed position. An abutment or stop member 195 is secured upon the outer end of plunger 192 and limits movement thereof inward or rearward through the bracket 192. A bell crank lever 197 is pivotally mounted, within channel member 45, upon a pin 198 secured in the forward flange of this channel member. Lower arm 199 of lever 197 normally is disposed in horizontal position and extends above the flat upper end of bill 183 of latch member 180, as will be clear from Figures 18 and 20. The other arm 200 of lever 197 extends upward above pin 198 and is connected at its upper end, by a link 201, to the upper end of a cam member 202, pivoted upon a pin 203 secured to the forward flange of channel member 45. Lower arm portion 204 of cam member 202 is urged downwardly by a leaf spring 205 bearing on the upper surface of such lower portion, this leaf spring being secured, at its outer end, in a pin 206 which is secured in the outer flange of channel member 45. When the bed plate 46 is in its lowered position, cam member 202 is held in the dotted line position shown in Figure 21, by the leaf spring 205, movement of this cam member in a counterclockwise direction being limited by a stop pin 207 secured in the front flange of channel member 45. Upon movement of the cover 92 into open position, and resulting release and upward movement of the bed plate 46, arm 56 of the lefthand bracket 55 contacts the lower portion of cam member 204, as the bed plate 46 reaches its full raised position, turning the cam member 202, from its dotted line position shown in Figure 21 clockwise into its full line position shown in that figure. Such movement of the cam member 202 causes turning of the bell crank lever 197 in clockwise direction, as viewed in Figure 18, thus forcing the latch member 180 downward and releasing the door 134, this door being then swung in opening direction by means of the spring pressed plunger 191. In that manner, when it is desired to use the machine for ironing purposes, movement of cover 92 into open position serves to move the door 135 into open position beneath the cover, serving as a support therefor, releases the bed plate 46 and permits movement thereof into full raised position, and also causes door 134 to be released and moved in opening direction.

When cover 92 has been moved into full open position, the ironing means is exposed available for use and the open end of the ironing members 7 and 8 is disposed above and adjacent the left-hand end member 40 of the enclosing structure. The lefthand door 134 may then be disposed in position to provide a support for articles being ironed and which extend outward beyond the lefthand end of the ironing roll and shoe 7 and 8. That disposition of the articles being ironed is necessary in many cases, as when ironing articles of greater width than the length of the roll, ironing the cuffs and collar bands of shirts, or 75 when ironing dresses or other articles, areas of

which are passed between the lefthand end portion only of the roll and the shoe.

Referring to Figures 22, 24, and 25, the lefthand door 134 is swung from its full open position, shown at A in dot and dash lines, into position B shown in dotted line, extending outward from the outer face of end member 40, adjacent the front thereof. In this latter position of door 134, the left end wall thereof (when closed) is disposed adjacent the outer wall of end member 40. Door 134 may then be swung upward from its position B, shown in Figure 22, into horizontal position above the top of bracket 169, as shown in Figure 23. It is supported in the latter position in a suitable manner, conveniently by means of a foldable brace, of known type, comprising two links 210 and 211, pivotally connected at 212, link 210 being pivoted at 213 to a bracket 214 secured to the inner face of the front wall of door 134, and link 211 being pivoted at its other end, at 214a, to a lug 215 of bracket 169. This brace is provided with known means 216 effective to prevent folding upward thereof, when the brace is extended, it being then effective for holding the door 134 in horizontal position. In order to prevent swinging of the door from out of the position shown in Figure 25, which is its position shown also in Figure 23, a bolt 217 is slidably mounted in keepers 218 secured to the inner face of the front wall of door 134, adjacent the bottom wall or flange thereof. This bolt operates through an opening 219 in the lefthand end wall or flange (when closed) of door 134, which flange is disposed adjacent the outer face of end member 40, when the door 134 is in its horizontal position shown in Figures 23 and 25. In this position of the door, opening 219 is disposed in alignment with an opening 220 in the outer wall of end member 40 and an opening 221 in the bracket 128, as will be clear from Figure 28. Bolt 217 is then projected to extend through the aligned openings 219, 220, and 221, and is effective for locking the door 134 against swinging movement. This will be clear from Figure 28, in which the position of the door shown in Figure 25 is indicated in dotted lines, the bolt 217 being shown in dotted lines as extending through the openings referred to. When door 134 is in the position in Figure 25, it projects lengthwise from end member 40, so that the full length of this door is available for supporting articles being ironed, and extending outward beyond the lefthand end of the ironing members, that position of the door being preferable when the articles are of such character as to extend a considerable distance lengthwise of the machine, as distinguished from extending a considerable distance from front to back of the machine. In the latter case, it is preferable to dispose door 134 so that the length thereof extends transversely of the machine, that is, from front to back thereof. In order so to position door 134, it is turned, while in the position of Figure 22, about arm 170 of bail 167 from position B of Figure 24 in a counterclockwise direction, as viewed from above, as indicated by the arrow b, into substantially the position C, and bail 167 is swung about the axis of arm 166 thereof, the door 134 moving from the position B of Figure 24 in the direction of the arrow c into the position D, adjacent and parallel to the outer wall of end member 40, with its top wall or flange adjacent the top of this end member. At that time the bracket 169 occupies the position shown in Figure 26. Door 134 is then swung upward about pintle rod 178, into horizontal position, in which

position it is supported by the hinged brace previously referred to. After the door has been thus positioned, it is secured against swinging movement on or with the bail 167, by means of a bolt 223 slideable through keepers 224 secured to the inner face of the front wall of door 134, adjacent the left end wall or flange thereof (when the door is in closed position). Bolt 223 is aligned with an opening 225 through the top wall or flange of door 134, which opening is aligned with an opening 226 in the outer wall of end member 40 and an opening 227 in bracket 128, when door 134 is in the position shown in Figures 2, 26, 27, and 28. Bolt 223, when projected, extends through the aligned openings 225, 226, and 227 and effectively locks the door 134 in position with its length extending transversely of end member 40, at the top thereof and projecting outward therefrom. This door is then available for supporting articles being ironed and projecting beyond the lefthand end of the ironing members, in substantially the same manner as when the door is disposed as in Figure 25, except that it is disposed at right angles to its position shown in the latter figure so as to support more satisfactorily, under certain conditions above referred to, articles which might not be supported entirely satisfactorily by the door positioned as in Figure 25. There is thus a distinct advantage in being able to dispose door 134 in either of two positions in cooperating relation to the ironing members.

When it is no longer desired to use the machine for ironing, the door 134 may be lowered into vertical position, by breaking the brace comprising the links 210 and 211 downward, and then swinging the door downward, as indicated in Figure 27, about pintle rod 178 into its vertical position. The door may then be swung into closed position, in an obvious manner, or may be left in open position, if it is desired to utilize the enclosing structure as a writing desk or for analogous purposes. In cases where it is desired to use the lefthand portion only of cover 92 for writing or like purposes, it may suffice to have only door 134 in open position. Where a greater space is desired, however, the righthand door 135 may also be moved into open position, as above described. Also, in cases where the lefthand portion of cover 92 is, for any reason, not available as use for a writing desk, by opening the righthand door 135 the righthand portion of the cover may be utilized for that purpose. There is thus a distinct advantage in providing two doors either or both of which may be opened, as desired to render either the entire area, or a selected portion thereof, of the cover 92 available for use as a writing desk or table and like purposes.

In the modified form shown in Figures 30 to 34, inclusive, flange 93 of cover 92a is spaced slightly above the top walls of the end members 40 and 41 of the enclosing structure, and above the channel member 45 and the top walls of the doors 134 and 135, when the latter are closed and the cover is in closed position. Conveniently, suitable spacing elements or bosses 230 are struck downward from flange 93 of cover 92a and provide spacing elements for the purpose stated. Flange 93 may be provided with any other suitable downward projections providing spacing elements. It will be understood that certain of the spacing elements are disposed to seat upon the top wall of the righthand end member 41, in the full open position of cover 92a, there being a spacing member, in the form of a washer 231

disposed about stud 143 of pin 142, between element 141 and flange 93 of the cover, there also being a spacing washer 232 disposed about pivot pin 94 between the top wall of end member 41 and flange 93 of cover 92a. By spacing the cover from the associated elements of the enclosing structure, in the above manner, the total area of contact between the cover and such elements is greatly reduced, resulting in corresponding reduction in frictional resistance to movement of the cover in opening and closing thereof, which is advantageous in facilitating such movement of the cover. In order further to facilitate movement of the cover, the latter is provided, adjacent its lefthand end, with a transverse strip 233, the end portions of which overlie and are secured to the front and the rear portions of flange 93, the portion of the strip between these flanges being offset downward with its underside flush with the underside of flange 93. A roller 234, preferably rubber covered, is supported for rotation in the upper portion of channel member 45, by means of supporting straps, one of which is shown at 235. Roller 234 projects upward through an opening 236 in the top wall of channel member 45, the forward portion of flange 93 resting upon this roller, when the cover 92a is in closed position. In the opening movement of the cover, strip 233 passes on to roller 234, as the forward portion of flange 93 passes out of contact with the roller, and the rearward portion of flange 93 passes on to roller 234 as strip 233 passes out of contact with the roller. It will be understood that the referred to portions of flange 93, and the strip 233, contact roller 234 in the reverse order, during closing movement of the cover. The roller 234 may project above member 45 an appropriate distance such as to maintain the spacing elements or projection 230 spaced a slight distance above the top wall of the end members and the channel member, thus reducing liability of marring of the structure by the spacing element in the movement of the cover, these spacing elements serving to prevent downward movement of the cover to an objectionable extent, when it is subjected to downward pressure in its closed position. Under such conditions, the cover is supported by the roller 234 and may readily be moved into open and closed positions with little effort.

In the modified form shown in Figures 35 to 37, a compensating member 238 is eccentrically pivoted, at 239, within each of the end members of the enclosing structure. A cable 240 passes about member 238 and upward therefrom over a grooved pulley 241 rotatably mounted in the end member adjacent the top thereof, from which pulley the cable extends downward and has its adjacent end secured to a pin 242 projecting from a bracket 243, secured to and depending from bed plate 46 adjacent the end thereof. The inner wall of each end member is provided, adjacent the top thereof, with an opening 244, of appropriate size and shape to accommodate the run of cable 240 between pulley 241 and pin 242, in the movement of bed plate 46. Figure 37 shows the opening 244 and the mounting of pulley 241. A coil tension spring 245 has its upper end anchored to the other end of cable 240, the lower end of this spring being anchored to bracket 66. Cable 240 is suitably secured to member 239, at 246, at an appropriate point of the periphery thereof. When bed plate 46 is in its full raised position shown in Figure 35, spring 245 is under minimum tension. At that time

lever arm X through which the spring acts is of maximum length, and is much greater than lever arm Y through which the weight of the bed plate and the parts carried thereby acts, the latter lever arm being then of minimum length. It will be understood that the bed plate 46 may be held in raised position by the latch means previously referred to, such means not being shown in Figure 35 for clearness of illustration. Movement of bed plate 46 from its raised position downward into the enclosing structure into its lowered position, indicated by the dot and dash lines, imparts turning movement to the compensation member 238, which turning movement is effective for decreasing the length of the lever arm through which the spring acts, while increasing the length of the lever arm through which the weight of the bed plate 46 and the parts carried thereby acts. It will thus be seen that as the bed plate 46 moves from horizontal position toward vertical position, with the weight thereof becoming decreasingly effective as to the compensating member 238, the length of the lever arm through which this weight acts is increased, whereas the length of the spring lever arm is decreased as the tension of the spring is increased. In the upward movement of the plate 46 the reverse action occurs, the length of the lever arm through which the weight acts decreasing and the length of the spring lever arm increasing as the tension of the spring decreases. In that manner I compensate for differences in the effective weight of bed plate 46 and the parts carried thereby, with respect to member 238, and the variation in tension of spring 245, so that the force exerted by this spring and effective on plate 46 is substantially constant throughout the movement of this plate in either direction. That renders it possible to raise and lower plate 46 with but little effort and guard against objectionable jarring of, and possible injury to, the machine due to violent raising or lowering of the bed plate 46.

The compensating member 238 has been illustrated, for example, as of circular outline. It may be of any other suitable outline depending upon requirements, as will be understood. Conveniently, member 238 is mounted for rotation upon a pin 239 secured in a collar 247 welded or otherwise suitably secured to a wall of the end member within which the compensating member 238 is disposed. The latter member may be mounted in any other suitable manner.

As has been indicated above, and will be understood by those skilled in this art, changes in construction and arrangement of parts of my invention may be resorted to, without departing from the field and scope thereof, and I intend to include all such variations, as fall within the scope of the appended claims, in this application in which the preferred forms only of my invention have been disclosed.

I claim:

1. In an ironing machine cabinet, an enclosing structure comprising end members, an ironer support member hinged on said end members, ironing means mounted on said support member, said support member and ironing means being movable into a lowered enclosed position within said structure, means for moving said support member and ironing means to a raised exposed operating position, and enclosure means for the front of said structure comprising a door movable from closed vertical position to an open horizontal position extending endwise from one end

member adjacent the top thereof to provide a support for articles being ironed.

2. In an ironing machine cabinet, an enclosing structure comprising end members, an ironer support member hingedly supported from said end members, ironing means mounted on said support member, said support member and ironing means being movable into a lowered enclosed position within said structure, means for moving said support member and ironing means to a raised exposed operating position, enclosure means for the front of said structure comprising a door movable from closed vertical position to an open horizontal position extending endwise from one end member adjacent the top therof to provide a support for articles being ironed, and a cover for said structure pivotally mounted adjacent a rear corner thereof and movable to a position at right angles to the enclosing structure and extending forwardly at one end thereof to provide a work shelf.

3. In an instrument cabinet, an enclosing structure comprising end members, a support member hingedly supported from said end members, an instrument mounted on said support member, said support member and instrument being movable into a lowered enclosed position within said structure, means for moving said support member and instrument to a raised exposed operating position, a cover for said structure pivotally mounted adjacent a rear corner thereof and movable to a position at right angles to the enclosing structure and extending forwardly at one end thereof to provide a work shelf, and closure means for the front of said structure comprising two doors, one movable from a closed vertical position to an open horizontal position extending endwise from one end member and the other movable from closed position to an open position to provide a support for said cover.

4. In an instrument cabinet, an enclosing structure comprising end members, a support member hingedly supported from said end members, an instrument mounted on said support member, said support member and instrument being movable into a lowered enclosed position within said structure, means for moving said support member and instrument to a raised exposed operating position, a cover for said structure pivotally mounted adjacent a rear corner thereof and movable to a position at right angles to the enclosing structure and extending forwardly at one end thereof to provide a work shelf, closure means for the front of said structure comprising two doors, one movable from a closed vertical position to an open horizontal position extending endwise from one end member and the other movable from closed position to an open position to provide a support for said cover, and means connecting said support door with the cover whereby the door coacts with the movement of the cover.

5. In an instrument cabinet, an enclosing structure comprising end members, a bed plate pivoted adjacent its rearward edge between said end members having limited downward movement therebetween and normally providing a closure for the back of said structure, an instrument carried by said plate movable upward therewith into position above said structure available for use, a cover removably mounted on said structure and movable into position to project forwardly of said structure at one end thereof, and doors hinged to said end members normally closing the front of said structure and movable into open positions independently of said cover.

6. In an instrument cabinet, an enclosing structure comprising end members, a bed plate pivoted adjacent its rearward edge between said end members having limited downward movement

5 therebetween and normally providing a closure for the back of said structure, an instrument carried by said plate movable upward therewith into position above said structure available for use, a cover for said structure pivoted at a rear-

10 ward corner to one of said end members for movement into position to project forwardly of said structure at said one end member, closure means for the front of said structure comprising a door hinged to said one end member, connections between said cover and said door for opening and closing the latter in the movement of said cover to open and closed positions, and means for disconnecting said door from said cover for opening and closing independently thereof.

20 7. In an ironing machine cabinet, an enclosing structure comprising end members, a bed plate pivoted adjacent its rearward edge between said end members having limited downward movement

therebetween and normally providing a closure
25 for the back of said structure, ironing means
carried by said plate movable upward therewith
into position above said structure available for
use in case removable mounted on said struc-

use, a cover removably mounted on said structure and movable into position to project forwardly of said structure at one end member thereof, and closure means for the front of said structure comprising a door having multiple hinge

structure comprising a door having multiple hinge connection to the other end member movable into open and closed positions independently of said cover and into position extending endwise from the outer face of said other end member adjacent the top thereof providing a support for articles being ironed.

articles being tested.

8. In an instrument cabinet, an enclosing structure comprising end members, a bed plate piv-

40 said springing and locking, said plate being located adjacent its rearward edge between said end members having limited downward movement therebetween, spring means to urge said plate upward, locking means releasably holding said bed

45 plate in lowered position, an instrument carried by said bed plate movable therewith upward into position above said structure available for use, latch means for releasably securing said bed plate

50 in raised position, a cover pivoted at a rearward corner to one of said end members movable into open position projecting forwardly from said one end member, and means supplementary to said latch means for releasing said locking means when said cover is in open position, said cover 55 having means cooperating with said latch means for limiting opening of said cover.

for limiting opening of said cover.

60 plate pivoted adjacent its rearward edge between said end members having limited downward movement therebetween, spring means to urge said plate upward, locking means releasably holding said bed plate in lowered position, ironing

means carried by said bed plate movable therewith upward into position above said structure available for use, latch means for releasably securing said bed plate in raised position, a cover

70 pivoted at a rearward corner to one of said end members movable into open position projecting forwardly from said one end member, and means supplementary to said latch means operated by movement of said cover into open position effective for releasing said locking means.

10. In an instrument cabinet, an enclosing structure comprising end members, a bed plate

pivoted adjacent its rearward edge between said end members having limited downward movement therebetween, spring means to urge said plate upward locking means releasably holding said bed plate in lowered position, an instrument carried by said bed plate movable therewith upward into position above said structure available for use, latch means for releasably securing said bed plate in raised position, a cover pivoted at a rearward corner to one of said end members movable into open position projecting forwardly from said one end member, and means operated by movement of said cover into open position effective for releasing said locking means.

11. In an ironing machine cabinet, an enclosing structure comprising end members, a bed plate pivoted adjacent its rearward edge between said end members having limited downward movement therebetween, spring means to urge said plate upward locking means releasably holding said bed plate in lowered position, ironing means carried by said bed plate movable therewith upward into position above said structure available for use, latch means for releasably securing said bed plate in raised position, a cover pivoted at a rearward corner to one of said end members movable into open position projecting forwardly from said one end member, and means supplementary to said latch means operated by movement of said cover into open position effective for releasing said locking means and limiting opening of said cover.

12. In an instrument cabinet, an enclosing structure comprising end members, a bed plate pivoted adjacent its rearward edge between said end members having limited downward movement therebetween, spring means to urge said plate upward locking means releasably holding said bed plate in lowered position, an instrument carried by said bed plate movable therewith upward into position above said structure available for use, latch means for releasably securing said bed plate in raised position, lost motion operating connections between said latch means and said locking means, a cover pivoted at a rearward corner to one of said end members movable into open position projecting forwardly therefrom, and means carried by said cover cooperating with said latch means for releasing said locking means in the opening of said cover and limiting opening of the latter.

13. In an ironing machine cabinet, an enclosing structure comprising end members, a bed plate pivoted adjacent its rearward edge between said end members having limited downward movement therebetween, spring means to urge said plate upward locking means releasably holding said bed plate in lowered position, ironing means carried by said bed plate movable therewith upward into position above said structure available for use, latch means for releasably securing said bed plate in raised position, lost motion operating connections between said latch means and said locking means, a cover pivoted at a rearward corner to one of said end members movable into open position projecting forwardly therefrom, closure means for the front of said structure comprising a door hinged to said one end member underlying said cover, connections between said cover and said door for opening and closing the latter in the movement of said cover into open and closed positions, and means carried by said cover cooperating with said latch means for releasing said locking means in the opening of said cover and limiting opening of the latter.

14. In an instrument cabinet, an enclosing structure comprising end members, a bed plate pivoted adjacent its rearward edge between said end members having limited downward movement therebetween and normally providing a closure for the back of said structure, an instrument carried by said plate movable upward therewith into position above said structure available for use, a cover removably mounted on said structure and movable into position to project forwardly of said structure at one end member thereof, closure means for the front of said structure comprising a door having multiple hinge connection to the other end member movable into position extending from the outer face of the latter adjacent the top thereof, yielding means urging said door in opening direction, latch means holding said door closed, and means actuated by said bed plate as it approaches raised position for releasing said latch means.

15. In an ironing machine cabinet, an enclosing structure comprising end members, a bed plate pivoted adjacent its rearward edge between said end members having limited downward movement therebetween, means yieldingly urging said bed plate upwardly, locking means releasably holding said bed plate in lowered position, ironing means carried by said bed plate movable therewith upward into position above said structure available for use, latch means for releasably securing said bed plate in raised position, a cover pivoted at a rearward corner to one of said end members movable into open position projecting forwardly from said one end member, means releasably securing said cover closed, closure means for the front of said structure comprising two doors, one hinged to said one end member underlying the forward portion of said cover, spring means urging said door in opening direction, the other having multiple hinge connection to the other end member and being movable into position extending from the outer face of said other end member adjacent the top thereof, and sliding pivot connections between said cover and said one door for opening and closing the latter in accordance with opening and closing of said cover.

16. In an instrument cabinet, an enclosing structure comprising end members, a bed plate pivoted adjacent its rearward edge between said end members having limited downward movement therebetween and normally providing a closure for the back of said structure, an instrument carried by said plate movable upward therewith into position above said structure available for use, a cover for said structure movable into position to project forwardly of said structure at one end member thereof, closure means for the front of said structure comprising a first door hinged to one of said end members movable into open position beneath said cover providing a support therefor in the open position thereof and a second door, a bail comprising two vertical arms, means comprising hinge links connecting one arm of said bail to the other end member for relative pivotal and swinging movements, a bracket pivoted on the other arm of said bail, means connecting said second door adjacent the top thereof to the top of said bracket for movement about an axis perpendicular to said other arm of said bail into normal position parallel with said bracket and raised position perpendicular to said bracket, brace means connecting said bracket and door for releasably holding the latter in raised position, and means for releasably securing said second door in

raised position extending from the outer face of said other end member.

17. In an ironing machine cabinet, an enclosing structure comprising end members, a bed plate pivoted adjacent its rearward edge between said end members having limited downward movement therebetween and normally providing a closure for the back of said structure, ironing means carried by said plate movable upward therewith into position above said structure available for use, a cover for said structure movable into position to project forwardly of said structure at one end member thereof, closure means for the front of said structure comprising a first door hinged to one of said end members movable into open position beneath said cover providing a support therefor in the open position thereof and a second door, universal connections between the other end member and said second door permitting movement of the latter from closed position into position extending from the other end member adjacent the top thereof and perpendicular thereto, and means for releasably securing said second door in said latter position.

18. In an instrument cabinet, an enclosing structure comprising end members, a bed plate pivoted adjacent its rearward edge between said end members having limited downward movement therebetween and normally providing a closure for the back of said structure, an instrument carried by said plate movable upward therewith into position above said structure available for use, a cover for said structure movable into position to project forwardly of said structure at one end member thereof, closure means for the front of said structure comprising a first door hinged to one of said end members movable into open position beneath said cover providing a support therefor in the open position thereof and a second door, universal connections between the other end member and said second door permitting movement of the latter from closed position into position extending from the other end member adjacent the top thereof and perpendicular thereto, means for releasably securing said second door in said latter position, and means for releasably securing said second door closed and confining it against lengthwise movement.

19. In an ironing machine cabinet, an enclosing structure comprising end members, a bed plate pivoted adjacent its rearward edge between said end members having limited downward movement therebetween and normally providing a closure for the back of said structure, ironing means carried by said plate movable upward therewith into position above said structure available for use, a cover for said structure movable into position to project forwardly of said structure at one end member thereof, closure means for the front of said structure comprising a first door hinged to one of said end members movable into open position beneath said cover providing a support therefor in the open position thereof and a second door, universal connections between the other end member and said second door permitting movement of the latter from closed position into either of two positions at right angles one to the other and extending from the other end member adjacent the top thereof and perpendicular thereto, and means for releasably securing said second door in either of said two positions.

20. In an ironing machine cabinet, an enclosing structure comprising end members, a bed plate pivoted between said end members having limited

downward movement therebetween and normally providing a closure for said structure, ironing means carried by said plate movable upward therewith into position above said structure available for use, compensating members eccentrically pivoted on the respective end members, cables windable onto and off of said compensating members secured at one end to said plate for raising the latter and controlling lowering thereof, and a tension spring secured to the other end of the respective cables and anchored to said structure.

21. In an ironing machine cabinet, an enclosing structure comprising end members, a support member hinged on said end members, ironing means mounted on said support member and movable into exposed position available for ironing, a cover pivoted at one rearward corner to one of said members for movement into position extending forwardly from said one member, said other end member and said cover having openings aligned when said cover is fully closed, a spring pressed latch having a locking element engageable through said aligned openings, means for moving said latch into releasing position when the cover is closed, and means for moving the latch into inoperative position during closing of the cover and releasing it for movement into operative position when the cover is fully closed.

22. In an instrument cabinet, an enclosing structure comprising end members, a support member hinged on said end members, an instrument mounted on said support member and movable into exposed position available for ironing, a cover pivoted at one rearward corner to one of said members for movement into position extending forwardly from said one member, said other end member and said cover having openings aligned when said cover is fully closed, a spring pressed latch having a locking element engageable through said aligned openings, means yieldingly urging said cover in opening direction, means for moving said latch into releasing position when said cover is closed, and means for moving said latch into inoperative position during closing of said cover and releasing it for movement into operative position when the cover is fully closed.

23. In an ironing machine cabinet, an enclosing structure comprising end members, ironing means housed within said structure and mounted therein for movement through the top thereof into exposed position available for ironing, a cover pivoted at one rearward corner to one of said members for movement into position extending forwardly from said one member, elements projecting from the underside of said cover spacing the latter from said end members, and a roller mounted on said structure, said cover having an element traveling upon said roller during opening and closing of said cover.

24. In combination, a frame, a vertically disposed front panel, a horizontal top panel for substantially covering the top of said frame, said top panel being hinged on a vertical pivot at one end of said frame and adapted to open by movement on its pivot into position to provide a shelf at the end of said frame, said front panel being hinged on a vertical axis extending along a front edge of said frame and adapted to open into supporting position under said top panel by substantially more than 90° of movement on its pivot, and a connection between said panels compelling opening thereof in unison.

25. In combination, a frame, a shiftable machine carrying bed plate mounted on said frame,

a vertically disposed front panel, a horizontal top panel for substantially covering the top of said frame, said top panel being hinged on a vertical pivot at one end of said frame and adapted to open by movement on its pivot into position to provide a shelf at the end of said frame, said front panel being hinged on a vertical axis extending along a front edge of said frame and adapted to open into supporting position under said top panel by substantially more than 90° of movement on its pivot, and automatic means releasable by opening movement of one of said panels for shifting said bed plate.

26. In combination, a frame, a vertically disposed front panel, a horizontal top panel for substantially covering the top of said frame, said top panel being hinged on a vertical pivot at one end of said frame and adapted to open by movement on its pivot into position to provide a shelf at the end of said frame, said front panel being hinged on a vertical axis extending along a front edge of said frame and adapted to open into supporting position under said top panel by substantially more than 90° of movement on its pivot, a connection between said panels compelling opening and closing thereof in unison, and a projection on said front panel spacing said top panel above said frame and providing clearance between the top of the latter and said top panel throughout the movement of said panels.

27. In an instrument cabinet, an oblong enclosing structure comprising spaced apart end members, an oblong cover for said structure movable to an open position at right angles to said structure adjacent one of said end members and extending forwardly therefrom, closure means for the front of said structure comprising a door hinged to said one end member, and connections between said cover and said door for opening and closing the latter incident to the movement of said cover to open and closed positions.

28. In an instrument cabinet, an oblong enclosing structure comprising spaced apart end members, an instrument supporting bed plate pivoted adjacent its rearward edge between said end members and having limited downward movement therebetween and normally providing a closure for the back of said structure, an instrument carried by said plate and movable upward therewith into position above said structure available for use, an oblong cover for said structure movable to an open position at right angles to said structure adjacent one of said end members and extending forwardly therefrom, closure means for the front of said structure comprising a door hinged to said one end member, and connections between said cover and said door for opening and closing the latter incident to the movement of said cover to open and closed positions.

29. In an instrument cabinet, an enclosing structure comprising end members, a cover for said structure pivoted at a rearward corner to one of said end members for movement into position to project forwardly of said structure at said one end member, closure means for the front of said structure comprising a door hinged to said one end member, and connections between said cover and said door for opening and closing the latter incident to the movement of said cover to open and closed positions.

30. In an instrument cabinet, an enclosing structure comprising end members, an instrument supporting bed plate pivoted adjacent its rearward edge between said end members and

having limited downward movement therebetween and normally providing a closure for the back of said structure, an instrument carried by said plate and movable upward therewith into position above said structure available for use, a cover for said structure pivoted at a rearward corner to one of said end members for movement into position to project forwardly of said structure at said one end member, closure means for the front of said structure comprising a door hinged to said one end member, and connections between said cover and said door for opening and closing the latter incident to the movement of said cover to open and closed positions.

31. In an instrument cabinet, an oblong enclosing structure comprising spaced apart end members, an oblong cover for said structure movable to an open position at right angles to said structure adjacent one of said end members and extending forwardly therefrom, closure means for the front of said structure comprising a door hinged to said one end member, an interengaging tongue and slot connections between said cover and said door for opening and closing the latter incident to the movement of said cover to open and closed positions.

32. In an instrument cabinet, an oblong enclosing structure comprising spaced apart end members, an oblong cover for said structure movable to an open position at right angles to said structure adjacent one of said end members and extending forwardly therefrom, closure means for the front of said structure comprising a door hinged to said one end member, and connections between said cover and said door for opening and closing the latter incident to the movement of said cover to open and closed positions, said connections including a pin carried on the cover positioned for cooperative engagement in a slot formed in the top wall of said door.

33. In an instrument cabinet, an oblong enclosing structure comprising spaced apart end members, an oblong cover for said structure movable to an open position at right angles to said structure adjacent one of said end members and extending forwardly therefrom, closure means for the front of said structure comprising a door hinged to said one end member, and interengaging tongue and slot connections between said cover and said door for opening and closing the latter incident to the movement of said cover to open and closed positions, said connections including a depending headed pin positioned for interlocking engagement in a slot formed in the top wall of said door.

34. In an instrument cabinet, an enclosing structure comprising end members, a cover for said structure pivoted at a rearward corner to one of said end members for movement into position to project forwardly of said structure at said one end member, closure means for the front of said structure comprising a door hinged to said one end member, and connections between said cover and said door for opening and closing the latter incident to the movement of said cover to open and closed positions, said connections including a depending pin carried by the cover positioned for cooperative engagement in a slot formed in the top wall of the door, said slot being dimensioned so that the end thereof serves as a stop for the said pin for limiting the outward swinging movement of the cover about its pivotal connection to said structure.

DAVID A. LUNDY.
